UNITED STATES PATENT OFFICE.

ABRAHAM ROCKOWITZ, OF NEW YORK, N. Y., ASSIGNOR OF ONE-HALF TO LOUIS MARGOLIS, OF NEW YORK, N. Y.

CORSET-FASTENER.

1,079,921.

Specification of Letters Patent. Patented Nov. 25, 1913.

Application filed March 7, 1913. Serial No. 752,542.

To all whom it may concern:

Be it known that I, ABRAHAM ROCKOWITZ, a resident of the borough of the Bronx, city, county, and State of New York, have invented certain new and useful Improvements in Corset-Fasteners, of which the following is a specification.

My invention relates to a device to be used in connection with corsets by means of which the corset may be more readily unfastened than is the corset provided only with the usual eye and button clasp. This last named fastening necessitates either further drawing the corset together in front or loosening the laces in order to disengage the eyes from the buttons. This drawing the corset together is not only difficult and uncomfortable but very frequently results in breaking the steels. The difficulty is increased by the fact that the wearer's figure is usually larger at night when the corset is to be removed than in the morning when it is put on.

The object of my invention is the production of a fastening means for the corset which permits the corset to be unfastened without this additional drawing of the corset together or loosening of the laces.

A further object of my invention is the production of such a fastening means which shall be applicable to corsets already provided with the ordinary eye and button clasp.

To this end my invention consists in the peculiar arrangement, construction and combination of parts hereinafter more fully described and claimed.

In the accompanying sheet of drawings which form a part of this application—Fig. 1 is a perspective of a corset provided with the invention, the corset being shown fastened together. Fig. 2 is a detail of the eye side of the corset shown in perspective. Fig. 3 is a perspective of the fastening means, and Fig. 4 is a vertical section of Fig. 3.

The corset 1 has on one side in front eyes 2 fastened to the front steel of that side in any convenient manner, and to the front steel on the opposite side buttons 3 being thus made like any ordinary corset.

The fastening device 4 comprises two resilient strips, the upper strip 5 being superimposed upon the lower strip 6 and the whole being inclosed in fabric forming a

fly 7. To the upper strip 5 are fastened eyes 8 provided at the rear with staples 9, these eyes and staples being positioned to engage with the buttons 3 and the eyes 2 respectively when the device is in use, and each eye 8 and staple 9 being conveniently made of one piece of metal. The upper strip 5 has slots 10 in line with the staples. Projecting through these slots are hooks 11 which are rigidly attached to the lower strip 6. These hooks are progressive in length and engage the staples 9, projecting sufficiently above the fabric inclosing the strips to permit them to lie over the eyes 2 when the device is attached to the eye side of the corset. The progression in length of the hooks is such that when they are moved downward for engagement with the staples they engage the staples one at a time and when in position in the staples the shortest of the hooks shall be sufficiently engaged with its staple to make a strong firm fastening.

Suitable means are provided for sliding the hooks 11 into and out of engagement with the staples 9 and for holding them in engagement therewith. For this purpose I have shown a slot 12 in the upper strip 5, in which slides an eye 13 rigidly fastened to the lower strip 6 and provided with a strap 85 or tape 14 having one member 15 of a snap for engagement with the other member 16 fastened to the upper strip 5, the snap is so placed as to hold the tape taut when in position in the staples the shortest engagement. The upward movement of the hooks should be sufficient to permit the lower end of the longest of the hooks to be slid beyond the eye of the corset held thereby so that the eye readily disengages itself 95 from its staple.

It is customary to fasten the skirts of corsets together with hooks and eyes. Skirt hooks 17 are accordingly shown on the skirt on one side of the corset and skirt eyes 18 on the skirt of the other side. At the bottom of the fabric inclosing the two resilient strips are skirt hooks 19 provided at the rear with skirt eyes 20. These are positioned for engagement with the skirt eyes 18 and skirt hooks 17 respectively.

The operation of the device is as follows: The device is fastened to the eye side of the corset by placing the staples 9 through the eyes 2; the hooks 11 are then slid over the

tops of the eyes and into engagement with the staples 9. The progressive lengths of the hooks permit the wearer to slide them over the eyes and into engagement with the staples one at a time, thus enabling the wearer to hold the parts in place, in case they become sprung in wearing, and to rigidly attach the fastening device to the corset. The tape 14 is then drawn taut and held by the snap 15, 16, making it impossible for the hooks to slide out of position during wear. The skirt hooks 17 can then conveniently be engaged with the skirt eyes 20. The corset is then ready to be put on in the ordinary manner, the eyes 8 being snapped over the buttons 3 and the skirt hooks 19 caught in the skirt eyes 18. When it is desired to remove the corset the snap 15, 16 is disengaged and the hooks 11 pulled out of engagement with staples 9 and eyes 2 allowing said eyes to slide over and out of engagement with the staples, thus unfastening the corset without having to draw it tighter together or unloosen the laces as would be necessary in disengaging the eyes 2 or 9 from the buttons 3. The skirt hooks are readily disengaged, and the eyes 8 lifted from the buttons 3. The device is then ready to be replaced on the eye side of the corset as above set forth.

30 It is to be understood that I do not desire to be limited to the exact details shown and described, for obviously modifications will occur to those skilled in the art.

What I claim as new, and desire to secure by Letters Patent of the United States, is—

1. An auxiliary fastening means for corsets adapted to be used in conjunction with the usual corset-fastening means, provided with a series of eye-plates adapted to take over the buttons on one of the corset steels, staples adapted to extend through the slots on the other corset steel, and a series of connected auxiliary locking devices adapted to lock said staples within said slots, substantially as described.
2. An auxiliary fastening strip for corsets adapted to be used between the usual corset-fastening means, comprising a series of eye-plates mounted on said strip adapted to take over the buttons on one of the corset steels, staples formed on said eye-plates adapted to extend through the slots on the other corset steel, and a series of connected auxiliary locking devices movable on said strip and adapted to lock said staples within said slots, substantially as described.
3. An auxiliary fastening means for corsets adapted to be used in conjunction with the usual corset-fastening means, provided with a series of eye-plates adapted to take over the buttons on one of the corset steels, staples adapted to extend through the slots

on the other corset steel, and a series of connected simultaneously movable hooks of progressively greater length disposed adjacent said staples and adapted to be progressively moved through said staples above said eyes when said eyes and staples are in engagement, substantially as described.

4. An auxiliary fastening means for corsets adapted to be used in conjunction with the usual corset-fastening means, provided with a series of eye-plates adapted to take over the buttons on one of the corset steels, staples adapted to extend through the slots on the other corset steel, a series of connected auxiliary locking devices adapted to lock said staples within said slots, and means for maintaining the locking devices in engagement with the staples, substantially as described.

5. An auxiliary fastening means for corsets adapted to be used in conjunction with the usual corset-fastening means, provided with a series of eye-plates adapted to take over the buttons on one of the corset steels, staples adapted to extend through the slots on the other corset steel, a series of connected auxiliary locking devices adapted to lock said staples within said slots, and means for moving the locking devices into and out of engagement with the staples, substantially as described.

6. An auxiliary fastening means for corsets adapted to be used in conjunction with the usual corset-fastening means, provided with a series of eye-plates adapted to take over the buttons on one of the corset steels, staples adapted to extend through the slots on the other corset steel, a series of connected auxiliary locking devices adapted to lock said staples within said slots, and means for moving the locking devices into and out of engagement with the staples and for maintaining them in engagement therewith, substantially as described.

7. A multiple fastener for corsets comprising a series of eyes and a series of staples adapted to be disposed through said eyes, a locking means for said staples comprising a series of connected simultaneously movable hooks of progressively greater length disposed adjacent said staples and adapted to be progressively moved through said staples above said eyes when said eyes and staples are in engagement, substantially as described.

Signed at New York in the county of New York, State of New York, the 5th day of March, 1913.
